(57) **CLAIM**

The ornamental design for a bandages pouch, as shown and described.

DESCRIPTION

FIG. 1 is a perspective view of a bandages pouch showing our new design;

FIG. 2 is a top plan view of the bandages pouch;

FIG. 3 is a bottom plan view of the bandages pouch;

FIG. 4 is a first end elevational view of the bandages pouch;

FIG. 5 is a second end elevational view of the bandages pouch; and,

FIG. 6 is a side elevational view, the opposite side elevational view thereof being the same.
